UNITED STATES PATENT OFFICE.

CLAUDE WELLS LONG, OF ST. LOUIS, MISSOURI.

RACK FOR HOLDING PHONOGRAPH-RECORDS.

No. 867,986.

Specification of Letters Patent.

Patented Oct. 15, 1907.

Application filed May 10, 1907. Serial No. 372,996.

To all whom it may concern:

Be it known that I, CLAUDE WELLS LONG, a citizen of the United States, residing at St. Louis, Missouri, have invented a certain new and useful Improvement 5 in Racks for Holding Phonograph-Records, of which the following is a full, clear, and exact description, such as will enable others skilled in the art to which it appertains to make and use the same, reference being had to the accompanying drawings, forming part of 10 this specification, in which—

Figure 1 is a perspective view showing a rack constructed in accordance with my invention; Fig. 2 is a cross sectional view through the upper portion of the rack and shows the manner in which the partition rods 15 are retained in position; and Fig. 3 is a cross sectional view of a portion of the rack showing the means for supporting the shelves intermediate their ends.

This invention relates to a new and useful improvement in racks for holding disk-shaped phonograph 20 records.

One object of my invention is to provide a rack for the purpose described which can be built at a low cost and shipped in "knock-down" form to a dealer.

Another object is to provide a rack in which the supporting shelves are so constructed that accidental displacement of the records is prevented and dust or dirt 25 cannot accumulate on the shelves. And still another object of my invention is to provide a rack that presents a neat and ornamental appearance and which 30 will effectively display the records arranged therein.

Referring to the drawings which represent the preferred form of my invention, I designates the end pieces of the rack between which are arranged horizontal shelves for supporting the disk-shaped phonograph records. Each of these shelves consists of two strips 25 35 40 45 50 55 60 65 70 75 80 85 90 95 100 strips 2 preferably of wood, that are mortised into the end pieces 1 and are arranged at a slight angle to each other with a space 3 between their inner edges, as shown in Figs. 2 and 3. By constructing the shelves in this manner the records 4 are prevented from rolling off the shelves as they will seat themselves between the oppositely inclined strips 2 and any dust or dirt that settles on the shelves will drop through the openings 3.

The rack is provided with vertical partitions to support the records in an approximately upright position, said partitions being formed by a plurality of continuous rods 5 that extend from the top to the bottom of the rack. These rods may be either wood or metal, those herein shown consisting of pieces of heavy wire provided at their upper ends with lateral extensions 6 that rest upon the top piece 7 of the rack; each parti-

tion being preferably formed by two rods. The strips 2 which form the shelves of the rack are supported intermediate their ends by a plurality of sleeves 8 that surround the rods 5, said sleeves preferably consisting of short pieces of metal tubing, as shown in Fig. 3, and if desired, washers 9 can be interposed between the ends of the sleeves and the strips 2 to prevent the ends of the sleeves from cutting into said strips. Racks of this description can be built in large numbers at a factory where machine tools and other labor-saving devices are used, thereby enabling the racks to be produced at a low cost. They can then be shipped in "knock-down" form to dealers who can assemble them without the aid of a skilled mechanic, the rack 65 being assembled by simply inserting the shelf-pieces 2 in the grooves formed in the end pieces 1 and then dropping the rods 5 into position, the shelf-pieces 2 being provided with holes through which the rods extend. As the rods 5 are of small diameter they will 70 not be conspicuous so that the vertical partitions will hardly be perceptible to a person looking at the rack, thereby causing the rack to look as though it were filled even if there is only one record between each partition.

Another desirable feature of my improved rack is that the shelves will not sag when they carry a heavy load as each of the shelf-pieces 2 is supported at a plurality of points intermediate its ends by means of the sleeves 8.

Preferably, pieces of molding 10 are arranged at the top and bottom of the rack to present a finished appearance thereto and if desired the shelf-piece 2 can be permanently connected to the end pieces 1 by means of fastening devices 11.

Having thus described my invention, what I claim as new and desire to secure by Letters Patent is:

A knock-down rack for holding phonograph records, comprising end pieces and a top piece detachably connected together, the end pieces being provided on their inner sides with oppositely inclined grooves, horizontally disposed strips arranged in said grooves to form shelves, a plurality of removable continuous rods extending through the shelf-pieces to form vertical partitions, the upper ends of said rods being bent laterally so that they will rest upon the top piece of the rack, and pieces of ornamental molding at the top and bottom of the rack; substantially as described.

In testimony whereof I hereunto affix my signature in the presence of two witnesses, this seventh day of May 1907.

CLAUDE WELLS LONG.
